UNITED STATES PATENT OFFICE.

FRANK WM. BOWLER, OF CHICAGO, ILLINOIS.

REVERSIBLE WINDOW.

1,427,088.

Specification of Letters Patent. Patented Aug. 29, 1922.

Application filed August 2, 1920. Serial No. 400,759.

To all whom it may concern:

Be it known that I, FRANK W. BOWLER, a citizen of the United States, and a resident of Chicago, in the county of Cook and 5 State of Illinois, have invented a new and useful Improvement in Reversible Windows, of which the following is a full, clear, and exact description.

My invention relates to improvements in 10 reversible windows, and it consists in the combinations, constructions, and arrangements herein described and claimed.

An object of my invention is to provide a window construction having glass carrying 15 sashes slideable vertically in an ordinary manner and also arranged to be revolvable at will in either raised or lowered position to permit cleaning both sides of the window without danger or inconvenience to the 20 operative.

A further object of my invention is to provide a device of the type described that has means for rendering the same weather-proof.

25 A further object of my invention is to provide in a device of the type described a sash construction that can be used with window frames of an ordinary construction without the necessity of changing the construction of the latter.

30 A further object of my invention is to provide a device of the type described that is simple in construction, not likely to get out of order easily, relatively inexpensive to 35 manufacture, and thoroughly practical commercially.

Other objects and advantages will appear 40 in the following specification, and the novel features of the invention will be particularly pointed out in the appended claims.

45 My invention is illustrated in the accompanying drawings, forming part of this application, in which

Fig. 1 is a front elevation showing the use 50 and application of the preferred form of the device,

Fig. 2 is a section along the line 2—2 of Fig. 1,

Fig. 3 is a section along the line 3—3 of 55 Fig. 1,

Fig. 4 is a side elevation, partly in section, of a portion of the device,

Fig. 5 is a detailed sectional view of a portion of the preferred form of the device,

55 Fig. 6 is a detailed sectional view of an

other portion of the preferred form of the device,

Fig. 7 is a detail of certain elements incorporated in the preferred form of the device.

Figure 8 is an enlarged detail of a fragmentary portion of the structure shown in Figure 2.

I am aware that a reversible window broadly is not new.

Referring now to the drawings in which the same reference numerals are used for the same parts throughout the views, it will be noted that I show in Fig. 1 an ordinary window frame construction in which the 70 fixed outer side frame members are denoted by 1, the top by 2, and the sill by 3. Inner side frame members 4 are spaced from the outer side frame members 1 by vertical members 5 and 6, thereby providing a compartment 7 at each side of the window for housing counterweights 8. The vertical members 6, which as well as the members 5, are disposed at right angles to the outer side members 1, are extended inwardly, as 80 best seen in Fig. 3. Vertical weather strips 9 are secured to the outer side of the vertical members 6 in close contact with the projecting portion of a wall 10. Strips 11 of molding or the like are also secured to the 85 outer side of members 6 in contact with the inner edge of the weather strips 9, as shown. Vertically disposed pieces of molding 12 may be provided to cover the inner edges of the outer side frame members 1 and the 90 members 5.

Vertical spacing bars 13 have a portion disposed in grooves 14 in the inner sides of the inner fixed side frame members 4 to form with the projecting ends of the members 6 a guideway 15 for the reception of a slidable sash. Additional vertical spacing members 16 are secured to the inner side frame member 4 to provide with the spacing bars 13 a second guideway 17 for the reception of an additional slidable sash. The parts described so far are ordinary in construction and form no part of my invention except in so far as they cooperate with the parts about to be described.

In the ordinary window construction the upper sash is slidably disposed in the guideway 15 which is the outer of the two guideways, while the lower sash is slidably disposed in the guideway 17.

In carrying out my invention, I provide a sash carrying casing 18 that is slidably disposed in the guideway 15. The sash carrying casing is formed with vertical channels 19 in its side members for the reception of sash cords 20 each of which has one end secured thereto in an ordinary manner and has its other end secured to one of a pair of counterweights 8. Each sash cord 20 extends 10 upwardly and is guided by a pulley or sheave 21 that is journaled in one of the inner side frame members 4 adjacent the upper end thereof.

Channels 22, arranged to face each other, 15 are secured to the inner edge of the members 6 (see Figures 3 and 6). A dummy sash 23, which has its side members reduced at 24 to enter the channel guideways 26, is slidable vertically therewith.

20 The slidable movement of the dummy sash 23 is controlled by a plunger 27 formed with side arms 28 having a roller 29 journaled at 30 therebetween, since this plunger which is disposed in an opening 31 extending inwardly from each side edge of the side walls of the dummy sash 23 is pressed outwardly by the action of a compression spring 32. A rolling contact is thereby established with the inner wall of the channel 22, whereby the 25 dummy sash 23 will be maintained in any position along the channel guideway and may be moved slidably therewith at will. I also provide means for locking the dummy sash 23 in its raised or lowered position, such means consisting of a lock 33 preferably of a flush bolt type disposed in a recess 34 in the side member of the dummy sash 23 and provided with a bolt 35 that can be moved selectively into or withdrawn from a slot 36 provided through the channel 22 intermediate its length into the member 6 or a similar slot 37 through the channel 22 into the member 6 adjacent the lower end thereof. The slidable movement of the sash carrier 18 30 is controlled by one pair of the counterweights 8, as stated. A glass holding sash 38, which is suitable in size to fit within the sash carrying frame 18, is provided with plates 39 countersunk in horizontally aligned recesses 40 in its side edges. These plates 39 have projecting studs 41 which may be moved into sockets 42 formed in plates 43 secured to the edges of the side walls of the sash carrying casing 18 through upwardly 35 extending side slots 44, whereby the casing 38 is revolvably supported by the sash carrying casing 18. The glass holding sash 38 is provided with a locking device 45 having a bolt 46 positioned to be moved selectively into one of the slots 47 and 48 provided in the top and bottom members of the sash carrying casing 18 to prevent the glass holding sash being revolved and to maintain the same in a vertical position, as pictured in 40 Fig. 1 of the drawings.

It will be understood that the dummy sash 23 and the sash carrying casing 18 in which the glass holding sash 38 is mounted form what is normally the upper half of a two-sash window. A second spacing member 49 is secured to each of the spacing members 13, as shown in Fig. 3 of the drawings, and channels 50, which are precisely identical with the channels 22 are secured to the members 13 and the spacing members 49 to provide a channel guideway for a second dummy sash 51. The dummy sash 51 and the parts appurtenant thereto are precisely identical in essential respects with the dummy sash 23 and consequently need not be described in detail. Corresponding precisely identical parts in the dummy sash 23 and the dummy sash 51 as well as any parts connected thereto have been designated by the same reference numerals.

Adjacent the dummy sash 51 is a second sash carrying casing 52 that is slidably disposed in guideway 17. The slidable movement of the sash carrying casing 52 is controlled by a second pair of counterweights 8 which are connected to the side members thereof by sash cords 53 that are passed around sheaves or pulleys 54 journaled in the inner side frame members 4 and secured to the side members of the sash carrying casing in an ordinary manner. A slot 55 is provided in the side edge of the sash carrying casing for the reception of the sash cord 53. It is to be noted that this slot 55 is deepened and extended to the spacing member 49, being wider than the similar slot 19 in the sides of the sash carrying casing 18, since the provision of the spacing member 49 positions the sash carrying casing 52 slightly farther from the center spacing bars 13 than is ordinary. Consequently, the slot 55 must be widened to accommodate the pulley 54 and to insure free movement of the sash cord 53 therein.

A second glass holding sash 56 is mounted in the sash carrying casing 52 in the same manner as the glass holding sash 38 is mounted in the sash carrying casing 18.

From the foregoing description of the various parts of the device, the operation thereof may be readily understood. The sides and the top and the bottom of the dummy sashes 23 and 51 extend inwardly beyond the inner edges of the sash carrying casings 18 and 52 respectively. Consequently, a window having this construction is thoroughly waterproof. The glass holding sashes 38 and 56 may be revolved at will to reverse the same when the dummy sashes have been moved vertically out of the way. Cleaning of both sides thereof by an operator standing within the room provided with my improved window construction may be accomplished. The glass holding sash 56 is provided with locking means for main- 130

taining the same in vertical position when desired. Such locking means are precisely identical with those described for the glass holding sash 38 and have been denoted by 5 the same reference numerals. The dummy sash 23 may be lowered or raised at will independently of the sash carrying casing 18. In other words either one of the pairs of dummy sashes and sash carrying casings 10 may be raised or lowered independently of each other and each element may be raised and lowered independently of the other elements in the sets of dummy sashes and sash carrying casings.

15 The glass holding sashes may be revolved in either raised or lowered position and may be partly revolved for ventilating purposes, if desired. I also provide means for locking one sash carrying casing in uppermost position, while the other set of dummy sash and sash carrying casing is located in lowered position. Such means comprise a pin 57 that can be projected through alined keepers 58 and 59 that are secured to the upper sides of 25 the dummy sash 51 and the sash carrying casing 52. The end of the pin or bolt 57 extends within a recess 60 in the bottom member of the sash carrying casing 18, wherefore the parts of the device are locked 30 in the position pictured in Fig. 2 of the drawings. The pin or bolt 57 is formed with a groove or slot 61 adapted to receive a finger 62 depending from the keeper 59, wherefore the pin or bolt 57 can not be 35 entirely withdrawn from the keeper 59.

It is obvious that the device described may be converted into a weightless window without departing from the spirit and scope of the invention, since automatic spring pressed 40 frictional means (not shown) may be disposed between the sides of the sash carrying casings 18 and 52 and the inner sides of the frame.

One of the advantages of the device lies in 45 the fact that the glass holding sashes may be instantly removed from the sash carrying frames for any purpose whatsoever and as quickly replaced without it being necessary to use any tools in accomplishing the removal. This is possible, since the glass holding sashes are maintained by their own 50 weight in pivotal relation with the sash carrying frames when the studs 41 have been moved into the sockets 42 through the upwardly inclined communicating slots 44 that 55 are open at their upper ends.

I claim:

1. A window construction comprising a stationary frame, a pair of sash carrying casings mounted therein for sliding movement, each in its vertical plane, glass holding sashes pivotally mounted in said sash carrying casings, a dummy sash arranged for sliding movement in a vertical plane between 60 said sash carrying casings, a second dummy sash arranged for sliding movement in a vertical plane contiguous to the outer of said sash carrying casings, said dummy sashes being slidable independently of the sash-carrying frames and, being formed to 70 extend inwardly beyond the inner edges of said sash carrying casings, whereby the window is weatherproofed and the revolvable sashes are prevented from being revolved when the dummy sashes are in certain positions. 75
2. A window construction comprising a stationary frame, a pair of sash carrying casings mounted therein for sliding movement, each in its vertical plane, glass holding sashes pivotally mounted in said sash carrying casings, a dummy sash arranged for sliding movement in a vertical plane between 80 said sash carrying casings, a second dummy sash arranged for sliding movement in a vertical plane contiguous to the outer of said sash carrying casings, said dummy sashes being formed to extend inwardly beyond the inner edges of said sash carrying casings, whereby the window is weatherproofed and the revolvable sashes are prevented from being revolved when the dummy sashes are in certain positions, counterweights and sash cords connected with said 85 sash carrying casings for controlling the sliding movement thereof, spring pressed means for controlling the sliding movement of said dummy sashes, and means for locking said dummy sashes in raised or lowered positions. 90
3. A window construction comprising a stationary frame, a pair of sash carrying casings mounted therein for sliding movement, each in its vertical plane, glass holding sashes pivotally mounted in said sash carrying casings, a dummy sash arranged for sliding movement in a vertical plane between 95 said sash carrying casings, a second dummy sash arranged for sliding movement in a vertical plane contiguous to the outer of said sash carrying casings, said dummy sashes being formed to extend inwardly beyond the inner edges of said sash carrying casings, whereby the window is weatherproofed and the revolvable sashes are prevented from being revolved when the dummy sashes are in certain positions, counterweights and sash cords connected with said sash carrying casings for controlling the sliding movement thereof, spring pressed means for controlling the sliding movement of said dummy sashes, and means for locking said dummy sashes in raised or lowered positions. 100
4. A window construction comprising a stationary frame, a pair of sash carrying casings mounted therein for sliding movement, each in its vertical plane, glass holding sashes pivotally mounted in said sash carrying casings, a dummy sash arranged for sliding movement in a vertical plane between 110 said sash carrying casings, said dummy sashes being formed to extend inwardly beyond the inner edges of said sash carrying casings, whereby the window is weatherproofed and the revolvable sashes are prevented from being revolved when the dummy sashes are in certain positions, counterweights and sash cords connected with said sash carrying casings for controlling the sliding movement thereof, spring pressed means for controlling the sliding movement of said dummy sashes, and means for locking said dummy sashes in raised or lowered positions, and locking means for locking said revolvable sashes in a vertical plane in either normal or reversed 115 position. 120
5. A window construction comprising a stationary frame, a pair of sash carrying casings mounted therein for sliding movement, each in its vertical plane, glass holding sashes pivotally mounted in said sash carrying casings, a dummy sash arranged for sliding movement in a vertical plane between 125 said sash carrying casings, a second dummy sash arranged for sliding movement in a vertical plane contiguous to the outer of said sash carrying casings, said dummy sashes being slidable independently of the sash-carrying frames and, being formed to 130 extend inwardly beyond the inner edges of said sash carrying casings, whereby the window is weatherproofed and the revolvable sashes are prevented from being revolved when the dummy sashes are in certain positions. 135

sashes pivotally mounted in said sash carrying casings, a dummy sash arranged for sliding movement in a vertical plane between said sash carrying casings, a second dummy sash arranged for sliding movement in a vertical plane contiguous to the outer of said sash carrying casings, said dummy sashes being formed to extend inwardly beyond the inner edges of said sash carrying casings, whereby the window is weatherproofed and the revolvable sashes are prevented from being revolved when the dummy sashes are in certain positions, counterweights and sash cords connected with said sash carrying cas-

ings for controlling the sliding movement thereof, spring pressed means for controlling the sliding movement of said dummy sashes, means for locking said dummy sashes in raised or lowered positions, locking means for locking said revolvable sashes in a vertical plane in either normal or reversed position, and means for locking one of said sash carrying casings in raised position and the other of said sash carrying casings and the dummy sash adjacent thereto in lowered position.

FRANK WM. BOWLER,
